UNITED STATES PATENT OFFICE.

CHARLES P. BOSSERT, OF MILWAUKEE, WISCONSIN, ASSIGNOR TO PFISTER & VOGEL LEATHER CO., OF MILWAUKEE, WISCONSIN, A CORPORATION OF WISCONSIN.

DRYING PROCESS AND APPARATUS.

1,046,254.

Specification of Letters Patent.

Patented Dec. 3, 1912.

Application filed April 4, 1910. Serial No. 553,377.

To all whom it may concern:

Be it known that I, CHARLES P. BOSSERT, a citizen of the United States, residing at Milwaukee, in the county of Milwaukee and 5 State of Wisconsin, have invented a certain new and Improved Drying Process and Apparatus, of which the following is a full, clear, concise, and exact description, reference being had to the accompanying drawings, forming a part of this specification.

My invention relates to drying processes and apparatus therefor.

Although the improvements which I propose may be used, as will be seen, in a great 15 many instances and in connection with various industries, I contemplate the use thereof particularly in tanneries, and will therefore describe my invention with this specific embodiment in mind so as to facilitate 20 the explanation thereof.

It will appear that the process and apparatus of my invention are peculiarly adapted to the drying of fibrous materials which may become more or less wet or, in fact, saturated, and it is clear, in view of this fact, 25 that my invention may be advantageously employed in connection with tanning processes. In such processes hides are brought into a thoroughly saturated state during 30 the tanning step in which they are subjected to the action of the various tanning solutions and, before the further dressing and currying processes, it is necessary that they be dried thoroughly.

From the following description of the process and the operation and construction of the apparatus of my invention in connection with its use in the tanning art, the adaptability thereof to many other similar 40 uses will become manifest.

In the known art it has been customary, in tanning establishments, to hang the wet hides in a room or chamber provided for that purpose, and to heat and ventilate that room 45 or chamber to a proper extent so that the drying of the hides may ensue. These rooms or chambers are heated by steam coils or in some other suitable manner, and the hides are hung about the room as best they can be 50 to save space. Considering the part this drying step plays in the complete tanning process, it will be understood why the most practical plan under this prior art arrangement was to transfer a certain lot of hides 55 after they had been removed from the tan-

ning pits or vats to this drying chamber and to allow them to remain in this chamber or room, under the influence of the heat and such draft as could be had, until they were thoroughly dried. The hides were then removed and the room or chamber was ready for the reception of another lot. In this practice it was found necessary to allow the hides to rest under those conditions for a period amounting, on the average, to about 60 eighteen hours, such a considerable length of time being required because of the fact that the hides could not be heated evenly nor disposed in a draft evenly, the moisture from some of the hides being transferred to others, depending upon the respective temperatures, and vice versa, with a gradual loss until all the moisture had become 65 evaporated.

It is the object of my invention to provide means whereby the hides, or for that matter, other articles, can be dried in a much shorter period and more thoroughly dried.

It is furthermore the object of my invention to provide a process and apparatus 80 which is consistent with the convenient and expeditious handling and manipulation of the hides.

It is the further object of my invention to provide a process and apparatus in which 85 regulation may be had to a degree and in which effective control may be had at all times. And it is the further object of my invention to carry out the proposed process by means of an apparatus of such simple design and construction that its cost would not 90 overbalance the practical advantages to be gained thereby.

The process of my invention includes the provision of a well-defined draft, preferably heated, entails the movement of the articles to be dried in such a draft against the direction of the draft, and the heating of the hides before they are introduced into the draft. The apparatus of my invention 100 provides for carrying out the process as thus outlined and for doing so, more specifically, in a definite manner. The apparatus which I propose is mainly and essentially in the form of a tunnel through which the 105 hides or other articles to be dried are carried. The wet hides are introduced at one end and are ejected at the other, and practice and experiment have proven that hides 110 may be thoroughly dried in the proposed

manner by timing the trip through the tunnel to one hour and a half, quite in contrast to the eighteen hours required by the means of the prior art, as hereinbefore pointed out.

5 The apparatus which I propose provides for affecting the hides uniformly and provides for their physical manipulation in an efficient and convenient manner. Once introduced into the tunnel, the hides need no 10 further attention, and the tunnel itself needs no further attention than to regulate the temperature.

15 The improvements I propose are carried out by an embodiment in the apparatus illustrated in the accompanying drawings, in which—

20 Figure 1 is a side elevational view thereof, showing its relation to the parts of the building in which it is set up, parts being broken away so that its proportionate length may be confined to the sheet; Fig. 2 is a plan view thereof; Fig. 3 is a partial cross-sectional view taken on the plane indicated by the line 3—3 of Fig. 2 and looking in 25 the direction indicated by the arrows, this part being near the ejecting end of the tunnel; Fig. 4 is a partial sectional view taken on the plane indicated by the line 4—4 of Fig. 1 and looking in the direction 30 indicated by the arrows, this part being at the entrance end of the tunnel; Fig. 5 is a sectional view of the part of the apparatus just below the part shown in Fig. 3, being therefore a section taken on the plane indicated 35 by the line 3—3 of Fig. 1; Fig. 6 is an end view of the tunnel, showing the entrance end, and Figs. 7, 8 and 9 are detail views which will be later referred to and which illustrate parts of the carrying mechanism.

40 Like reference numerals are applied to the same parts throughout the various figures.

45 The tunnel is shown at 10, the middle part thereof extending between two box portions 11 and 12, which are preferably mounted upon the floor 13, the part 10 being therefore quite in the form of a bridge. The tunnel comprising these three parts is preferably 50 constructed by means of a stout mechanically resistant framework comprising the uprights 14, 14 and suitable horizontal bars, the main horizontal supporting member being in the form of a U-bar 15 disposed 55 on each side of the structure. The U-bars 15 extend beyond the entrance box 11 to a considerable extent, for a purpose herein-after fully pointed out. The frame-work thus described is preferably provided with 60 an expanded metal or wire screen wall so as to form a foundation for the plaster walls, as shown in the drawings. Plaster walls are preferable since they do not radiate the heat to any substantial degree, and there- 65 fore serve to confine it to the most useful

region. It is the part 10 of the tunnel that primarily carries the current or draft of air, and this part is therefore made of such height as to accommodate, with a reasonable degree of fitness, a doubled hide, so that 70 when the tunnel is full the draft will be intercepted as much as possible and will find little or no path of low resistance. It is of course clear that a number of rows of hides can be sent through the tunnel, and 75 that the tunnel can be adapted therefor without departing from the spirit and scope of this invention.

80 The carrying mechanism is in the form of a pair of traveling chains, one on each side of the tunnel, which operate upon sprockets which are driven in some suitable manner. The sprockets at the exit end are indicated at 16, 16, and those at the entrance end are indicated at 17, 17. Those at one end may 85 be permanently mounted, while those at the other end are preferably adjustably mounted. In the present embodiment the sprockets 16, 16 are shown as mounted upon the stationarily confined shaft 18, while the 90 sprockets 17, 17 are shown as mounted upon the shaft 19, which is journaled in sliding boxes 20, 20 mounted in elongated frames 21, 21 secured in some suitable manner to the frame-work. The sliding boxes 20, 20 each 95 are provided with an adjusting screw 22 which has threaded engagement with a lug 23 on the frame 21, and it is clear that manipulation of the hand-wheel 24 will operate to tighten or loosen the corresponding 100 chain 25 which operates over the respective sprockets. The chains 25, 25 are provided with suitable, uniform, and laterally registering intervals with special links 26, 26, (Figs. 7 and 8) each of which is provided 105 with a lug 27, to which is secured, by means of rivets 28, 28, a T-bar 29, these T-bars extending between registering links, as is evident from the drawings. Placed in respective parallel proximity to the two sides of 110 each sprocket chain are the angle irons 30 and 31, the upper iron 30 being above the upper run of the sprocket chain, and the lower angle 31 being below the lower run of the sprocket chain. The purposes of these 115 angle irons will be presently apparent. Also secured to the lug 27 of each of the special links 26 of the sprocket chain is the lug 32, of the truck frame 33 which carries, in longitudinal alignment, the rollers 34, 34. These 120 rollers are adapted to ride upon the angle irons 30 and 31 so that the latter act as rails and, as will be clear, supporting rails. It is to be noted that only one side of the sprocket chain passes through the tunnel, the other 125 side passing out over the tunnel; the object of this arrangement will be pointed out later when the operation of the device is described. As best shown in Fig. 4, the hides are adapted to be hung on cross-bars ex- 130

tending longitudinally of the tunnel and transversely between adjacent T-bars, these cross-bars resting upon the flanges of the T-bars. As shown in Figs. 7, 8 and 9, each of the flanges of the T-bars is provided with a plurality of preferably regularly spaced struck-up portions 35, 35, which act as abutments for properly spacing the cross-bars 36, 36, which are removable and preferably 10 of wood so as to be light and so, conveniently handled. In hanging the hides on the carrying means, the hide is first placed over such a cross-bar or stick 36 and the stick is then hung between adjacent T-bars 15 against corresponding abutments 35, 35, in Fig. 9 the bars being preferably put in place from the right.

As will be later pointed out, the draft enters the tunnel from the end shown in Fig. 3, and it is therefore apparent that there must be some special construction for that end in order that the sprocket chain may pass out of the tunnel, since that arrangement is desirable, as will be pointed out. Referring to 25 Fig. 3, it will be seen that the tunnel at this point is made of slightly greater height than the greater portion of the part 10, as indicated at 37. The top wall which is thus auxiliary is above the rail 30, which I may 30 refer to as the "return" rail, and the opening which thus results is closed partly by the vertical portion 38 and mainly by a series of gates 39, 39 which are pivoted at 40, 40 to the frame-work, which extend 35 across the tunnel and rest upon the rails 30, 30, and which are inclined in the direction in which the upper run of the chain moves, so that they may automatically respond and allow the trucks and T-bars to 40 pass out of the auxiliary portion without interference. A number of such gates being provided, and being properly spaced, it is clear that when one of the gates is open one or more of the others is closed, and the draft 45 therefore finds no outlet at this point.

Beyond the exit end of the tunnel a chamber 41 is disposed, this chamber being in part a heating box and also providing means for conducting the air, freely admitted to 50 said heating box, to a rotary blower indicated at 42. Heating coils are shown at 43 and, as shown, the chamber or casing 41 is open at the end so that the air may be admitted thereto freely and may pass among 55 the heating coils, in which steam may be circulated, this action being encouraged by the operation of the fan 42 which, so far as the entrance of air to the heating box is concerned, acts as a suction element. The 60 fan 42 is connected at its outlet end with a pipe 44 which leads to the opening 45 in the end of the wall of the tunnel at its exit end (Fig. 3). The blower 42 is provided with a pulley 46 which is connected with 65 the pulley 47 on the jack shaft 48 by means

of a belt 49, this jack shaft being operatively connected with a rotating element 50 of a source of power by means of the pulley 51 and the belt 52. In order that the carrying mechanism may also be operated from the jack shaft a counter-shaft 53 is provided upon which tight and loose pulleys are arranged, the jack-shaft being permanently connected with the counter-shaft 53 by means of the belt 54, and the counter-shaft being connected with a pulley 55, mounted on the tunnel frame-work, by means of a belt 56 permanently connected with a loose element on the counter-shaft 53 and arranged to be brought in or out of service by means of the shifting fork 57 which is operated by means of a wheel 58 connected with a pulley 59 by means of a cord 60, this pulley 59 being operated in one direction or the other by means of the operating cords 61, 61 which carry the weights 62, 62 in an obvious manner. The pulley 55 is carried upon a shaft 63 which also carries a pinion 64 which, in turn, meshes with a gear 65 on the same shaft 18 90 with the sprockets 16. It is clear that the carrying arrangement may be brought into and out of service conveniently by a person at the entrance end of the tunnel by means of the arrangement thus described, it being 95 understood, however, that this is shown merely as an example and is not to be regarded as the measure of the scope of any phase of my invention.

About midway between the ends of the 100 tunnel and preferably toward the entrance end, an outlet 66 is provided, this outlet being in the nature of a tap from the tunnel so that the draft created by the blower 42 and passing through the tunnel will pass 105 out through this outlet and not through the entrance end of the tunnel. The outlet flue is in the form of a canopy 67, which is supplemented by a pipe 68 passing upwardly preferably through the roof and to the open 110 air where it is provided with suitable hoods 69, 69, for obvious purposes. The canopy 67 is provided with the pivoted gates 70, 70 constructed quite in accordance with the description of the gates 39, 39, so as to accommodate the return sides of the sprocket chains without interfering with the air current arrangement. The pipe 68 is provided with a fan 71 which is operated in some suitable manner, for instance by means of 115 gearing and shafting 72, and tends to create a draft upward so as to assist the fan 42 in creating and maintaining the particular circulation desired.

The box 11 at the entrance end of the tunnel is provided, at the bottom thereof, with steam coils 72, 72, or some other heating arrangement so that the hides as they are carried thereabove may be thoroughly heated 120 before they are introduced into the draft. 130

The steam coils preferably extend the entire length of the box so that sufficient heat may be had to secure the desired result, as will be pointed out when the operation of the arrangement is described.

It is clear from Fig. 3 that when a T-bar reaches the sprockets 16, 16 the main portion thereof will extend approximately radially from the center of the sprocket, 10 this action resulting in the lengthening of the distance between the rear flange of the T-bar and the forward flange of the T-bar following it, to such an extent that the cross-bars or sticks can no longer be held thereby 15 and they are dropped into the box 12, together with all the hides carried thereby. The bottom of the box 12 is open, as indicated at 73, but this opening is controlled by a sliding door 74 supported upon cross-beams 75, 75 carried upon rollers 76, 76 which ride upon rails 77, 77. The opening 73 is preferably made in the floor and, below the floor, is surrounded by a sash 78, the lower face of which is oblique to the 20 rails 77. The door 74 is also mounted so as to be oblique, or has a surface oblique to a similar degree, so that a wedge action is produced when the door is jammed shut, that is, when the door is rolled to the right 25 as far as it will go. In order that the joint between the door and the sash may be airtight, so far as possible, the sash or the door, or both, may be provided with a compressible washer member 79 of suitable material, for instance, a hide without the hair 30 removed. This has proved a very efficient joint, and the entire arrangement well fulfills the broad object of normally confining the draft to the tunnel proper. The door 35 carries a rack 80 which meshes with a pinion 81 operating on a relatively stationary shaft 82, this shaft also carrying the operating sprocket or sheave 83 which, in turn, carries the operating chain 84, adapted to be 40 manually operated, as is well known in other devices. Thus when a lot of hides falls from the carrying mechanism they fall down into the box 12 and upon the door 74, when warning may be given to the floor 45 below that the door may be shifted to remove all the hides and sticks which are carried thereby.

In order that access may be had to the various interiors for the purposes of adjustment, repair and regulation, manholes 50 may be provided. In order that regulation of temperature may be conveniently had, sight-holes 86, 86 may be provided in the tunnel, behind which thermometers may be placed, a glass cover being provided so that the heat may be confined.

The process of my invention and the manner in which it is carried out by the apparatus which I propose will now be described.

The blower 42, together with the auxiliary fan 71, maintains a constant current or draft from the exit end of the tunnel to the outlet 66, this draft or current being thoroughly heated by means of the heating arrangement 43, 43. By this arrangement the hottest and driest parts of the draft are at the exit end, the temperature being probably 170 or 180 degrees. Obviously the temperature decreases as the draft reaches the outlet, the temperature there being probably 100 degrees and, after wet hides are introduced, it is natural that the humidity should increase toward the outlet. It is of course well known that heating the hides assists in the evaporation of the solutions with which they are saturated, and not only is the heating proposed by the process of my invention advantageous for this purpose, but it also brings the hides to substantially the temperature of the draft before it is introduced into the same.

In carrying out my invention an operator is stationed at the entrance end of the tunnel, where he may operate the shifting mechanism for starting or stopping the carrying means. The carrying means is operated intermittently, in fact it is stationary most of the time. It is stationary while a lot of hides are put in place. When the parts are in the position shown in Fig. 4 the two T-bars farthest to the left in the figure are ready for the reception of the cross sticks carrying the hides. It is to be understood, of course, that the hides are hung only on the lower runs of the sprocket chains, since that part only passes through the tunnel. Thus as the T-bars come upon the lower angle rails 31, 31, as shown in Fig. 4, they are ready for the reception of a lot of hides. The carrying mechanism is stationary at this time, and the operator is provided with a large number of cross-sticks of proper length in addition to the hides which have just come from the tanning solutions and which are to be dried so that the further steps in the tanning process may be carried out. He places each hide over a stick and then places the stick between the two T-bars between which he is working. When the row is completed he operates the shifting cords 61, 61 to start the carrying mechanism, to move the hides farther on in the tunnel, and to bring the next T-bar down into place upon the lower rails 31, 31, so that another lot of hides may be put into position. It is clear that, continuing this operation, the hides are gradually passed over the heat coils in the box 11 and that they are heated to a considerable degree before they reach the draft which, so far as the tunnel is concerned, ends at the outlet 66.

As is well known in the art, moisture does not deposit much on a warm hide, while it does deposit upon a cold hide very rapidly.

The temperature of the hide controls the rate at which moisture deposits. It is further well known that a moist hide of a higher temperature will impart its moisture, 5 or a part thereof, to a colder hide and, consistently, a hide of a certain temperature being thoroughly wet will impart its moisture to another hide of the same temperature if it is not so wet. The importance of 10 systematic physical manipulation of the hides in accordance with the draft and the temperature is thus at once realized, for, in the drying chambers or rooms of the prior art, it is clear that moisture would be im- 15 parted from one to the other of the hides, and that the temperatures might affect them to no distinct advantage and so delay the entire process. The depositing of moisture upon a hide means that moisture is depos- 20 ited upon an oil which, itself, is over moisture, and this intermingling of oil and water gradually delays any kind of drying. Thus the primary heating of the hides is doubly important, for if it had no effect whatever 25 in securing primary evaporation it would be effective in bringing the hides to such temperature that they would not take on any of the moisture given off by those that pre- 30 ceded them. Thus if the hides are thor- 35oughly warm before they reach the draft, the moisture held by the air will not deposit upon the hides, but will pass out of the flue with the air, and only the primary moisture contained by the hides need be evaporated 40 by the draft into which they are to be intro- 45duced. The movement of the hides in a di- rection opposite to the direction of the heated air current is also important, for not only do the hides become more dry as they 50 move toward the exit end of the tunnel, but the air which affects them is also more dry. Consistently, they need not be brought up to such a great temperature near the end of 55 the draft, for there the temperature of the draft is considerably less than at the exit end. As the hides pass toward the exit end they are gradually subjected to greater heat and drier air until finally they may be ejected in a thoroughly dry condition. Only 60 one side of the carrier chain being led through the tunnel, it is clear that the hides will cover the cross-section as thoroughly as practicable, and there is no path of low resistance above the hides which the draft might otherwise find. As the hides enter the tunnel and gradually approach the end of the draft they become heated more and more until finally, just before they reach the draft, they are of approximately the 65 temperature of that end of the draft. Com- 70 ing into the draft the air is somewhat moist and the temperature slightly higher. Dur- 75 ing its travel as far as the draft it is likely that considerable of the moisture has been

evaporated from the hides, but I do not rely upon this feature for the proper operation 65 of my process. Having brought the hides to the desired temperature before they are introduced into the drying draft, the mois- 70 ture contained by the air of the draft, par- ticularly at the end thereof, will not tend to settle on the hides, but will, in fact, tend to take up more and so relieve the newly enter- 75 ing hides. The hides then gradually approach the exit end and, simultaneously, ap- 80 proach the higher temperature and drier air to secure the desired result, as hereinbefore pointed out.

It is clear that while a large number of 80 hides are physically handled at the same time they are also simultaneously acted upon in accordance with the process of my inven- 85 tion. The hides are constantly being intro- 90duced and accordingly being taken out of the tunnel, so that there is a complete cycle, 85 the greater portion of which involves the passage of the hides through the tunnel to secure the proper drying, as set forth.

I claim as new and desire to secure by Let- 90ters Patent:

1. A drying process consisting in con- 95 stantly maintaining a forced heated draft from the atmosphere through an inclosure and back to the atmosphere, primarily and independently dry-heating wet articles, then 100 introducing the heated wet articles into said draft by gradually shifting them from the primary heating zone to the zone of said draft, and then passing said articles through said draft.

2. A drying process consisting in con- 105 stantly maintaining a forced heated draft from the atmosphere through an inclosure and back to the atmosphere, primarily and independently dry-heating wet articles, then 110 introducing the heated wet articles into said draft by gradually shifting them from the primary heating zone to the zone of said draft, and then passing said articles through said draft in a direction opposite to that of the draft.

3. A drying process consisting in con- 115 stantly maintaining a forced heated draft from the atmosphere through an inclosure and back to the atmosphere, primarily and independently dry-heating wet articles to a temperature approximately equal to that of the colder end of said draft, then introduc- 120 ing the heated wet articles into said draft by gradually shifting them from the primary heating zone to the colder end of said draft, and then passing said articles through said draft.

4. A drying process consisting in con- 125 stantly maintaining a defined draft heated at the beginning thereof and passed from the atmosphere through an inclosure and back to the atmosphere, primarily and inde-

pendently heating wet articles to a temperature approximately equal to that of the end of the draft, then introducing the heated wet articles into said draft by gradually 5 shifting them from the primary heating zone to the zone of said draft, and then passing said articles through said draft.

5. A drying apparatus comprising a permanently open tunnel having an intermediate outlet to the atmosphere, heating means confined to one end of said tunnel, heating means independent of said first-named heating means confined to the other end of said tunnel, a blower associated with said last-named heating means and arranged to induce a draft toward said intermediate outlet, and a conveyer extending through said tunnel.

6. A drying apparatus comprising a permanently open tunnel having an intermediate outlet to the atmosphere, heating means at one end of said tunnel, heating means independent of said first-named heating means at the other end of said tunnel, an outlet in the floor of said tunnel at said last-named end, and a conveyer extending through said tunnel.

7. A drying apparatus comprising a permanently open tunnel having an intermediate outlet to the atmosphere, heating means confined to one end of said tunnel, heating means independent of said first-named heating means confined to the other end of said tunnel, a blower associated with said last-named heating means and arranged to induce a draft toward said intermediate outlet, a conveyer extending through said tunnel, a rotor, and means for driving said blower and said conveyer from said rotor.

40 8. A drying apparatus comprising a tunnel having an intermediate outlet, conveying mechanism therein, heating means at the entry end thereof, a floor outlet at the exit end thereof, an external box, a heater 45 in said box, a blower therein, and connection between the blower end of said box and the top of the tunnel at the exit end, the

other end of said box being open to the atmosphere.

9. In a drying apparatus, a tunnel, angle 50 irons extending lengthwise of said tunnel, an endless chain associated with each channel iron, carriers secured to certain links of said chain and having rollers riding on said angle irons, and cross-bars mounted between the carriers on one side and those on the other.

10. A drying apparatus comprising a permanently open tunnel having an intermediate outlet to the atmosphere, a conveyer 60 extending into said tunnel from the entry end nearly to the opposite end, an outlet door in the floor at the end of said conveyer, heating means confined to said opposite end of said tunnel, a blower associated with said heating means, said blower inducing a heated draft from said heating means to said intermediate outlet, and heating means independent of said first-named heating means confined to the entry end of the tunnel, the zone between that at said last-named heating means and said intermediate outlet being a graded zone subject to the induced heat from both means.

11. In a drying apparatus, a tunnel, carrying means in the form of a belt, one run only of which passes through said tunnel, supporting means carried by said belt, and a plurality of serially disposed automatically operated gates providing for the exit of 70 80 said supporting means.

12. In a drying apparatus, a tunnel, means for maintaining a draft in said tunnel, means for carrying a plurality of transversely extending T-beams through said tunnel, the flanges of said T-beams having struck-up portions to form abutments against which cross sticks may be laid.

In witness whereof, I hereunto subscribe my name this 30th day of March, A. D. 1910. 90

CHARLES P. BOSSERT.
